(57) **CLAIM**

The ornamental design for a light bar for use inside a vehicle, as shown and described.

DESCRIPTION

This invention is related to U.S. Pat. No. D489,144, issued Apr. 27, 2004, to William H. Dalton and assigned to the same Assignee as this application.

FIG. 1 is a bottom plan view of a light bar for use inside a vehicle, embodying my invention;

FIG. 2 is a front elevational view thereof;

FIG. 3 is a top plan view thereof; and,

FIG. 4 is a perspective view taken from the front thereof.
